UNITED STATES PATENT OFFICE.

CHARLES REMELIUS, OF NEW YORK, N. Y., ASSIGNOR TO COLUMBIA MACHINE WORKS & MALLEABLE IRON CO., OF BROOKLYN, NEW YORK, A CORPORATION OF NEW YORK.

MACHINE FOR REMOVING FROM AND REPLACING GEARS, &c., UPON SHAFTS.

No. 909,871.

Specification of Letters Patent.

Patented Jan. 12, 1909.

Application filed February 11, 1897. Serial No. 359,714.

To all whom it may concern:

Be it known that I, CHARLES REMELIUS, a citizen of the United States, residing at the borough of Manhattan, city, county, and State of New York, have invented an Improvement in Machines for Removing from and Replacing Gears, &c., upon Shafts, of which the following is a specification.

My invention relates to devices for removing or pulling off a gear-wheel or pulley from its shaft and afterward placing the same or a new one thereon. This is necessary either to take off an old or damaged wheel or pulley for repairs or to place on the shaft a new gear-wheel or pulley.

Heretofore devices for performing the function of pulling off a gear-wheel or pulley from a shaft have been employed, but these devices were not well adapted for wheels and pulleys of different sizes, for quick action, for adjustment according to the position and for a firm grip upon the structure to be removed, all of which it is the object of my present invention to make provision for.

In the device of my invention the centrally threaded power shaft is manually and quickly actuated by a hand-wheel and is so brought up to the work, after which power is applied by a lever and its pawl and a ratchet-wheel, the lever and pawl operating in either direction. This power shaft works through a swinging head pivotally mounted to a suitable base or standard so that an upward or downward inclination can be secured at once which will correspond with the inclination of a shaft from which a gear or wheel is to be removed. The gripping jaws are pivotally mounted upon this swinging head; they are set up to their work and are securely held in position by manually operated hand-wheels and screw shafts and these jaws can not slip or spring away from the work, all of which devices are hereinafter more fully described.

The devices for pulling on or replacing a gear or pulley on its shaft consist essentially of a pair of long arms or rods pivotally mounted to the respective ends of the swinging head and an apertured cross head.

In the drawing, Figure 1 is a vertical section and elevation of my improved structure, Fig. 2 is an end elevation of the same, Fig. 3 is a plan, Fig. 4 is a section through

the ends of the jaws upon the dotted line *x, x*, of Fig. 3, looking towards the gripping portions of the jaws, Fig. 5 is a side elevation of the disk bearer at the end of the shaft. Fig. 6 is a plan of a form of my invention and Fig. 7 is an elevation of the cross head member thereof.

The base or standard is shown as composed of the lower plate portion *a*, the vertical parallel ribs *a¹ a²* and the centrally disposed web *a³* which extends between the ribs *a¹ a²* and beyond at either side.

In suitable bearings near the upper ends of the ribs *a¹ a²* is received and mounted the pivot shaft *b*. A head *c* is mounted at an apertured depending portion thereof upon the pivot shaft *b* and this head is hollow-ended to receive the jaws *d e* which are pivotally connected to opposite portions of the said head by pivot pins *2 3*. These jaws *d e* are provided with outwardly extending shoulders *d¹ e¹* and in bearings formed with the opposite ends of the heads are screw-shafts *f g* provided with hand-wheels *f¹ g¹* by means of which the said screw shafts are rotated to bring their advancing ends *80* against the faces of the shoulders *d¹ e¹* so as to move the jaws *d e* up to their work, or in other words, up to the device that is mounted upon a shaft and which is to be engaged by the jaws and pulled off the shaft. The free ends of these jaws are provided with jaw end-plates or grippers which by preference are made with sharp edges and a screw-threaded shaft *h* passes centrally through an enlarged portion of the pivotally mounted head *c*.

As shown in Figs. 1 and 3, the free left-hand end of this shaft is apertured centrally to receive the pin of a disk bearer *h¹* which fits against the end of the shaft and which in turn bears against the shaft of the gear-wheel or pulley which is to be removed. On the opposite end of this shaft *h* I place a ratchet-wheel *i* and a hand-wheel *k*, the latter being on the extreme end of the shaft *100* and both of these parts keyed firmly in position.

I provide a lever having a forked lower end *l* and outer handle end *l¹*; the forked end of the lever straddles the ratchet-wheel *i* *105* and the shaft *h* passes through its members and in this forked end of the lever there is pivoted a pawl *6* adapted to swing through

the fork of the lever and its end made corresponding on each side so as to engage the teeth of the ratchet-wheel i in either direction.

In Figs. 1 and 3, m represents a shaft of a machine and m^1 a gear-wheel or pulley to be pulled off the said shaft, said parts being shown in their relation of action to the parts of my improved device.

10 The pivotally mounted head e may be swung into a downward or upward inclination according to the inclination of the shaft from which a gear or pulley is to be removed, or as shown in the drawing, this 15 head with its jaws may occupy a horizontal position providing the said shaft from which a gear or pulley is to be removed occupies a corresponding position. The beveled upper ends of the ribs a^1 a^2 limit the 20 swinging movement of the head e .

In the operation of the device of my improvement the hand-wheels f^1 g^1 with their screw-shafts f g are to be rotated so as to release the jaws d e and permit them to open 25 to such an extent that their free ends pass readily over outside of a gear or pinion such as m^1 . These hand-wheels and screw-shafts are then to be operated so as to close the jaws d e up against the sides or opposite 30 faces of the said gear or pinion so as to bring the end plates or gripping portions 4 5 behind the opposite edges of said gear or pinion, the jaws being thus held rigidly in place against accidental displacement. 35 The central shaft h is then revolved by means of the hand-wheel h^1 which performs the function of quickly running up the central shaft until its disk bearer h^1 comes in contact with the end of the shaft from which 40 the gear or wheel is to be removed. The lever-handle l^1 is then engaged by the hand and its pawl engaging the ratchet-wheel i turns the shaft with a slow powerful motion in a direction which forces the shaft through 45 the gear-wheel or pulley, while the same is being held by the pivoted jaws.

This position is shown in Figs. 1 and 3, and in which the said pulley m^1 is almost pulled off the enlarged portion of the shaft 50 on which it had been forced. At the same time that the pulley or wheel is released from the shaft the pawl l is swing over and the lever device operated to rotate the central shaft h to an appreciable extent so as to release the same from its grip upon the shaft after which the hand-wheel h^1 may be turned rapidly so as to draw the central shaft quickly out of the way. The gear or pulley is then to be engaged by a suitable 55 device and the jaws released by the manually actuated hand-wheels f^1 g^1 and their screw-shafts f g , and these movements are to be repeated with each gear-wheel or pulley pulled off its shaft.

60 The base or standard may be securely

fastened to a floor or the same may be heavy enough to maintain its position and I prefer that the jaw end-plates or grippers be removably secured to the free jaw end-faces as shown in Fig. 4, because should they be 70 damaged or broken they can be easily removed and replaced by new parts, and furthermore it is quite essential that these jaw end-plates or grippers should be of harder metal than is necessary for the rest of the 75 machine and their removability and separation is an essential feature because of the tempering and special treatment required for these parts.

In Figs. 6 and 7, I have reproduced the 80 parts shown in Fig. 3, and to which I have added the devices I prefer to employ for pulling or forcing a pinion or pulley on to its shaft. These comprise the long arms or rods n n^1 at one end connected to the outer 85 ends of the swinging head e^1 by pivot shafts 7 8. The other ends of these rods are screw-threaded and receive the adjusting nuts and washers 9 10. I provide a cross-head o with open jaw ends o^1 to fit removably upon the 90 rods n n^1 forward of the nuts and washers 9 10. This cross-head o is made with an enlarged central recess and apertured portion to receive the pinion or pulley and pass over the shaft.

In Fig. 6 r represents an armature of any 95 motor device, r^1 its shaft and r^2 a pinion. One end of the shaft is against the disk bearer h^1 and the pinion at the other end bears against the inner face of the recess of the head o and the operation of turning and advancing the screw as hereinbefore described forces the shaft r^1 along and pushes the pinion onto the shaft and into position.

The head o is readily lifted off of the rods 100 n n^1 and said rods with the short shafts 7 8 are advantageously removed from the swinging head for the use of the devices in pulling off a pinion or pulley from its shaft as hereinbefore described.

The device of my improvement is to be 105 made in various sizes, adapted for small, light and heavy work, even such small work as the pulling of watch and clock pinions off of their shafts and such heavy work as the 110 pulling of gears and pulleys off of main or armature shafts in various styles of motors; also and as hereinbefore described the device of my improvement is adapted to pull or force a pinion or pulley on its shaft.

I claim as my invention:

1. The combination with a suitable base 115 to rest upon a floor or foundation, of a head pivotally mounted thereon, jaws pivotally connected to the head and movable therewith, a screw-shaft movable in the head, means associated with the screw-shaft for rotating the same and means connected to the head for setting up the jaws to the work and holding them in position.

2. The combination with a suitable base to rest upon a floor or foundation, of a head mounted thereon, said head having an apertured and threaded center and recessed ends, jaws pivotally connected to the head in the recessed ends, bearings in the ends of said head, screw-shafts passing through said bearings and operative against the said jaws, a main screw-shaft passing through the apertured center of said head and means for rotating the same.

3. A device of the character described, comprising a base composed of a lower plate and parallel vertically disposed ribs, an intermediate stiffening web, bearings formed in the upper portion of the said ribs and a pivot shaft passing therethrough and across between the ribs, a head having a depending portion perforated for the said pivot shaft, the head being mounted in the base between the said parallel ribs and adapted to swing on the pivot shaft, means for limiting said swinging movement, a screw-shaft passing centrally through the head, means for rotating the screw-shaft, jaws pivoted to the head in the same horizontal plane as the screw-shaft and devices connected to the head adapted for setting up the jaws to the work and holding them in position, whereby the head may be brought into aline-

ment with the work and assume the same inclination.

4. In a device of the character described, the combination with a suitable base, of a head, a pivot shaft connecting the head to the base in a swinging relation, manually actuated pushing and pulling devices connected to the head and adapted to move with the swinging head into the line of inclination of the work to more readily engage the same.

5. In a device of the character described, the combination with a suitable base, of a head, a screw shaft mounted in the head, means for rotating the screw shaft, long rods and short shafts for pivotally mounting said rods at one end to the ends of the head, a cross-head with jaws to fit removably upon said rods and with an open center and enlarged central recess for receiving a shaft and engaging its pinion or pulley for pulling the same on the shaft, and means on the rods to resist the thrust of the cross-head.

Signed by me this 30th day of January 1907.

C. REMELIUS.
